Primary Examiner — John Windmuller*Assistant Examiner* — Luqman McNeil(74) *Attorney, Agent, or Firm* — Aka Chan LLP**CLAIM**

The ornamental design for an umbrella with solar panels, as shown and described.

DESCRIPTION

FIG. 1 shows a perspective view of a first embodiment of a design for an umbrella with solar panels.

FIG. 2 shows a top view of FIG. 1.

FIG. 3 shows a side view of FIG. 1.

FIG. 4 shows a perspective view of a second embodiment of a design for an umbrella with solar panels in an open position.

FIG. 5 shows a top view of FIG. 4.

FIG. 6 shows a first side view of FIG. 4; and,

FIG. 7 shows a second side view of FIG. 4, where the umbrella with solar panels is in a closed position.

The broken line showing is included for the purpose of illustrating environment and forms no part of the claimed design. The gray shading in the figures is surface shading that indicates claimed subject matter. The broken lines and unshaded surfaces form no part of the claimed design.
